FORMING METAL PARTS

Roy C. Ingersoll, Oak Park, Ill., assignor to Borg-Warner Corporation, Chicago, Ill., a corporation of Illinois

Application August 14, 1937, Serial No. 159,087

3 Claims. (Cl. 266—6)

This invention relates to an apparatus for quenching materials.

In the manufacture of certain articles, such as tie rods, axles and the like, it is necessary to condition the material for the use to which it is to be put, by suddenly cooling or quenching the material. Unless the material is controlled during the quenching, it may undergo a change in size or shape or both, with the result that portions which are to be held to predetermined dimensions and spacings do not measure up to the requirements set for them. In the case of tie rods, for example, it is necessary that the eyes be maintained at a predetermined spacing, but under the usual quenching procedure the rod undergoes such a change in size as to render it necessary to form the eyes separately and to weld them to the rod after the rod has been quenched to insure a proper spacing for the eyes.

The object of this invention is an improved apparatus by which materials may be quenched in their complete form without undergoing a material change in essential dimensions.

A feature of this invention is a die for holding the material while it is being quenched, the area of the material in contact with the die being a minimum to expose a large portion of the surface of the material to the action of a refrigerant.

Another feature of this invention is a means for maintaining a constant spacing for critical portions of the material to be quenched.

Still another feature, in a die for holding the material, is a series of jet forming means for projecting the refrigerant against the material.

Still another feature, in a die for holding the material, is a central chamber for equalizing the pressure and temperature of the refrigerant before it contacts the material.

These and other objects and features will become apparent from the following description when taken together with the accompanying drawings which form a part thereof and in which:

Fig. 1 is a side elevation in section of a quenching die embodying the principles of this invention;

Fig. 2 is a plan view of the bottom die showing a portion of a tie rod in place;

Fig. 3 is a side view of the bottom die;

Fig. 4 is a bottom view of the upper die and associated water system, with a portion of the die cut away to show the central chamber and jet forming means, and

Fig. 5 is a perspective of the portion of the die which holds the eye of the tie rod during the quenching.

The same reference characters are used to designate similar parts throughout the various figures of the drawings.

In its preferred form, this invention comprises a quenching die made up of a bottom die and an upper die. The bottom die is provided with a land for supporting the material to be quenched and with pins for pinning critically spaced portions of the material to the die. The upper die is provided with a central chamber which is connected by a series of passageways to recesses located over the material to be quenched. The recesses are separated by lands which contain a portion shaped to fit over and contact the material when the die is closed. The chamber is connected by pipes to a source of refrigerant, and a foot-operated valve controls the flow through the pipes. For purposes of illustration this invention will be described with reference to a quenching die for tie rods although it is adapted for use in connection with quenching other materials.

Referring now to the drawings for a detailed description of the invention, 10 is a bottom die which is provided with a raised portion or land 11 for supporting a tie rod 12. Immediately over bottom die 10 is the upper die 13 which is reciprocable with respect to bottom die 10 to permit the insertion and removal of tie rod 12 from the quenching die. Any suitable means for separating the upper and lower dies may be used. The upper die 13 is provided with a chamber 14 which is connected by one or more pipes 15 to a header 16. A refrigerant such as water under pressure supplied from a pump 35 is fed to header 16 through a control valve 17 and a flexible hose 18. Valve 17 may be operated by means of a pedal 19 connected through link 20 to valve 17.

Tie rod 12 is provided at its extremities with eyes 21, the spacing between which is assumed critical. Accordingly, bottom die 10 is provided with pins 22 which are adapted to be threaded through eyes 21 and through corresponding apertures 23 in machined inserts 24 secured to upper die 13. Pins 22 are designed to permit slight movement of the eyes in a direction which will not materially affect the spacing therebetween. Land 11 is preferably shaped so that it provides a line contact with tie rod 12. This type of contact insures a minimum area of the tie rod in contact with the land and consequently a maxi-

mum area of the tie rod exposed to the action of the refrigerant.

Immediately over tie rod 12, in upper die 13, is a plurality of recesses 25, separated by relatively thin lands 26. These recesses are connected to chamber 14 by means of jet forming passageways 27 which are inclined so as to direct a stream upon tie rod 12 when upper die 13 is lowered. To simplify the construction, one wall of recess 25 may be made substantially normal to the axis of passageways 27 to permit these passageways to be readily drilled from the outside. Lands 26 contain circular notches 28 which fit over tie rod 12 and clamp it to land 11 of bottom die 10. The edges 29 of notches 28 are rounded to decrease the area of tie rod 12 in contact with the notch.

It is apparent from Figure 1, that with tie rod 12 clamped between upper and lower dies 13 and 10 respectively, a space 30 is formed between the parts of the die by reason of land 11. Circulation of the refrigerant through the die is therefore accomplished from header 16 through chamber 14, passageways 27, recesses 25 and space 30 to the exterior of the die. Suitable drains (not shown) may be used for disposing of the water as it leaves the die.

The quenching of a tie rod is accomplished as follows:

30 The tie rod is first heated to a temperature at which internal stresses in the material are removed, and with upper die 13 raised, it is placed upon land 11 in its heated condition with pins 22 threaded through eyes 21. Tie rod 12 is previously formed by drop-forging or otherwise, and is substantially shaped as shown in Figure 2. With the hot rod in place, upper die 13 is lowered until the rod is clamped securely between notches 28 and land 11. Pin 22 is likewise threaded through aperture 23 and insert 24, and the rod is therefore held against vertical motion. Pins 22 are supported at both ends, i. e., they are held at one end by lower die 10 and at the other end by upper die 13, and are therefore fully capable of resisting any material changes in the spacing between eyes 21.

With tie rod 12 securely clamped between the upper and lower dies, foot pedal 19 is depressed, thereby opening valve 17 and admitting a refrigerant, such as water under pressure through flexible hose 18 and header 16 into chamber 14 wherein a uniform pressure is built up almost instantaneously. The water is then forcibly projected through passageways 27 upon the hot tie 55 rod 12, almost completely inundating the entire rod at once. The water then leaves the die through the space 30 between upper die 13 and lower die 10. The flow is allowed to continue for a few seconds and is then stopped by releasing foot pedal 19. Upper die 13 may then be raised and rod 12 removed from lower die 10.

Since the tie rod was heated to the temperature at which internal stresses are relieved, the quenching operation cools the rod through the 65 hardening and critical temperatures so that when the rod is removed from the quenching die, it is set and does not thereafter change its shape. While it was being cooled, however, it was constrained against motion in any direction 70 by the pins in the dies and by the clamping action of the lands between the jets on the upper die and the land on the lower die. It emerges from the die completely hardened and with no change in shape, and therefore requires no subsequent hand straightening operation before it is

ready for use. Since hand straightening operations are expensive, a great reduction is effected in the cost of making the tie rods.

The quenching action is extremely rapid due to the high velocity of the water, the simultaneous action of the jets and the large area of the rod exposed to the jets. Since chamber 14 is common to all of the passageways, the pressure at each passageway is the same, and the quenching action is therefore uniform along the entire 10 length of the rod. The flat land 11 used with the round rod insures a line contact between the rod and land and a maximum area of the rod exposed to the water.

It is understood that objects other than tie rods may be quenched in accordance with this invention and that the dies used therewith may be changed in accordance with the shape of such other objects. Similarly, other refrigerants beside water may be used. It is understood further that the foregoing description is merely illustrative of a preferred embodiment of the invention, and that the scope of the invention therefore is not to be limited thereto but is to be determined by the appended claims.

I claim:

1. In an apparatus for quenching a metal rod including means for holding said rod to prevent changes in shape tending to result from said quenching, and means for directing quenching liquid into contact with said rod, said first named means including a supporting member for said rod, and a second member for holding said rod against said supporting member including a series of flange-like walls extending from said second member and positioned along the length of said rod, each of said flange-like walls being formed with a recess therein effective to at least partially embrace said rod, said second named means comprising means for directing a plurality of separate streams of quenching liquid between successive ones of said walls and into contact with the intervening portions of said rod, said partially embracing recesses being effective to hold said rod tightly against said supporting member and being further effective to prevent movement of said rod in either a vertical direction or in a horizontal direction transverse to the axis of said rod.

2. In an apparatus for quenching a metal 50 automobile tie rod of a general U-shape and having fastening eyes adjacent the end portions thereof, means for directing quenching liquid into contact with said rod, and means for holding said rod against changes in shape in either a horizontal or a vertical direction, said holding means including a supporting member for supporting said U-shaped rod on one side thereof, and a second member for holding said rod against said supporting member, said second member comprising a series of flange-like walls extending from said second member and positioned along the length of said rod, each of said flange-like walls being formed with a recess therein effective to at least partially embrace said rod, spacing pins supported in at least one of said holding members and passing through said eyes adjacent the end portions of said U-shaped tie rod, said means for directing quenching fluid into contact with said rod comprising means for 65 directing a plurality of individual streams into contact with said rod and between successive ones of said walls, said partially embracing recesses being effective to hold said rod tightly against said supporting member and to pre- 75

vent movement of said rod in a vertical direction or in a horizontal direction transverse to the axis of said rod, said pin members being effective to maintain the spacing between the eyes formed in the end portions of said rod.

- 5 3. In an apparatus for quenching an automobile tie rod of a generally U-shape and having connecting eyes formed adjacent the end portions thereof, said rod being generally circular
10 10 in cross-section intermediate said eyes, said apparatus comprising a lower die member formed with a substantially plain supporting surface for supporting said tie rod intermediate said connecting eyes in tangential contact therewith, an
15 15 upper holding die for holding said intermediate portions of said tie rod in contact with said supporting surface formed with a series of recessed chambers in the under side thereof, said chambers being defined in part by downwardly ex-

tending separating flange-like partitions, each of said partitions being formed with an arcuate recess complementary in contour and in position to successive portions of said rod and at least partially embracing the same, a pair of pins supported in at least one of said die members and passing through said eyes in the end portions of said tie rod, means for introducing an individual stream of quenching medium into each of said recessed chambers and directing the same into contact with the intervening portions of said rod whereby to rapidly and uniformly quench said rod, said arcuate recesses being effective to prevent the movement of portions of said rod in contact therewith in either a horizontal or a vertical direction and said pin members being effective to maintain the spacing between said attaching eyes.

5 10 15 ROY C. INGERSOLL.
